UNITED STATES PATENT OFFICE

ROBERT H. PLASS, OF UPPER MONTCLAIR, NEW JERSEY, ASSIGNOR TO THE CHAPAL-
DONNER CORPORATION, OF NEWARK, NEW JERSEY, A CORPORATION OF NEW
JERSEY

FUR CUTTING MACHINE

Application filed June 20, 1931. Serial No. 545,792.

This invention relates to improvements in fur cutting machines for cutting animal pelts to remove fur from the skins thereof; such machines being commonly employed in the 5 hat manufacturing industry.

This invention has for its principal object to provide an improved construction of pelt feeding means adapted to feed the pelt to the cutting devices of the machine in such manner as to assure control of the pelt movement and support, especially as the last or trailing end portion thereof approaches the cutting point of the machine. To this end the novel feeding means of this invention comprises 10 means to support the pelt close to the cutting point, such means being so actuated as to provide clearance for the escape of severed fur from such cutting point, together with a reciprocatory means for engaging and impelling forward the pelt at points intermediate the usual feed rolls and cutting point, so that feeding movement is positively assured, especially as to the trailing end portions of 15 pelts after the same escape the nip of the main feeding rolls.

Other objects of this invention, not at this time more particularly enumerated, will be understood from the following detailed description of the same.

An illustrative embodiment of this invention is shown in the accompanying drawings, in which:

Fig. 1 is a top plan view of a fur cutting machine according to the principles of the present invention; Fig. 2 is a vertical transverse section of the same, taken on line 2—2 in Fig. 1; Fig. 3 is an enlarged fragmentary sectional view, illustrating the mode of operation of the pelt feeding means; and Fig. 4 is a detail fragmentary view, on an enlarged scale, showing the means for actuating the pelt supporting devices of the machine.

Similar characters of reference are employed in the above described views, to indicate corresponding parts.

Referring to said drawings, the reference character 5 indicates the end frame plates of the machine, between which extends an upwardly projected bed-knife support 6. Suitably journaled to extend between said end

frame plates 5 is a main shaft 7, upon which is fixed the cutting cylinder 8 of the machine. Radially projecting from the surface of said cylinder 8 are a plurality of revolving cutting blades 9, which are preferably of the usual helical or curved shape in longitudinal extension.

Fixed on said bed-knife support 6 is a stationary bed-knife 10 with which the cutting edges of the revolving cutting blades 9 cooperate with shearing effect. An enclosing hood 11 is arranged over the cutting cylinder 8 in such manner as to provide an opening 12 contiguous to the bed-knife 10 to give the pelts to be treated access to the cutting point of the machine. Extending downwardly from the exterior side of said bed-knife 10 is a severed fur discharge passage 13.

Suitably journaled to extend between said end frame plates 5, forwardly of the bed-knife 10, is a shaft 14 upon which are fixed lower feed rolls 15, and also journaled to extend between said end frame plates 5, above and parallel to said shaft 14 and lower feed rolls 15, is a shaft 16 upon which are fixed upper feed rolls 17 to cooperate with said lower feed rolls. Said shafts and their feed rolls are driven in opposite directions by any suitable transmission means, so as to engage a pelt passed between the rolls and urge the same toward the cutting point of the machine.

Illustrative of one form of such transmission means is the following arrangement. The main shaft 7 of the machine, which drives the cutting cylinder 8, is driven by the pulley 18, or equivalent means, from any suitable source of power. Journaled to extend between the end frame plates 5, preferably at the lower forward portions thereof, is a countershaft 19, which is connected with and driven by said main shaft 7 through a chain and sprocket transmission 20. Driven from said countershaft 19 is a chain and sprocket transmission 21, the driven sprocket 22 of which is journaled on a stud shaft 23. Connected with said driven sprocket 22, so as to rotate therewith, is a pinion 24, which meshes with a gear wheel 25 fixed on an end of the feed roll shaft 14, thus driving the same. Said feed roll shafts 14 and 16 are intergeared.

together by gearing 26, whereby the shaft 16 is driven from shaft 14, and in opposite directions. The upper shaft 16 and its feed rolls 17 are preferably tensionally urged toward the lower shaft 14 and its feed rolls 15 so as to grip a pelt passed therebetween in the usual manner.

The reference characters 27 and 28, respectively, indicate the members of two sets of longitudinally reciprocable bars, which bars respectively terminate at their inner ends in pelt supporting fingers 27' and 28' arranged to extend between the nip of the feed rolls 15-17 and the bed-knife 10, but in a plane 15 slightly below the plane of the nip of said feed rolls. Said bars and their fingers are disposed vertically edgewise to extend in substantially horizontal plane from the outer side or front of the machine toward the bed-knife; the same being supported at their outer end portions by a supporting plate 29, which extends between the end frame plates 5, and being supported at their inner end portions by the lower feed roll shaft 14 so as to pass between the rolls 15 thereof. A cover plate 30 extends from the outer side or front of the machine to terminate adjacent to the feed rolls 15-17, said cover plate serving to cover the major portions of the reciprocable bars 27-28, and its upper surface providing a feed table over which a pelt is fed to the nip of the feed rolls 15-17.

The means for reciprocating the bars 27-28 and their pelt supporting fingers 27'-28' comprises in one form, the following mechanism:

Pivots mounted on fulcrum studs 31, which project exteriorly from the end frame plates 5, preferably at each end of the machine, are inner lever members 32, which are inwardly off-set relative to said counter-shaft 19. Connected with and between the upper ends of said lever members 32 is a rod 33, which extends from end to end of the machine and beneath the reciprocable bars 27-28. Mounted on said rod 33 is an anti-friction roller or sleeve 34. Each bar 27 is provided at its under edge with a bifurcated or fork member 35 which straddles and is operatively engaged by the roller or sleeve 34. The lower end of each lever member 32 carries an anti-friction roller 36 which bears operatively against an actuating cam 37 which is fixed on and is rotated by said counter-shaft 19.

Pivots mounted on fulcrum studs 38, which also project exteriorly from said end frame plates 5 at each end of the machine, are outer lever members 39 which are outwardly off-set relative to said counter-shaft 19. Connected with and between the upper ends of said lever members 39 is a rod 40, which extends from end to end of the machine and beneath the reciprocable bars 27-28. Mounted on said rod 40 is an anti-

friction roller or sleeve 41. Each bar 28 is provided at its under edge with a bifurcated or fork member 42 which straddles and is operatively engaged by the roller or sleeve 41. The lower end of each lever member 39 carries an anti-friction roller 43 which bears operatively against an actuating cam 44 which is fixed on and is rotated by said counter-shaft 19.

The lower end portions of adjacent lever members 32-39 are interconnected by spring means 45, which operate to keep the former in actuated relation to their respective actuating cams 37-44.

The shape and setting of the cams 37 and 44 is such that the respective sets of bars 27 and 28, and their pelt supporting fingers 27' and 28', are alternately reciprocated in such manner that there is always one set of pelt supporting fingers inwardly moved to extend and lie between the nip of the feed rolls 15-17 and the bed-knife 10, so as to constantly support the pelt portions approaching the cutting point of the machine. When the sets of pelt supporting fingers are outwardly moved or withdrawn, clearance space is thereby provided for the escape from the cutting point of the machine of severed fur to the discharge passage 13. The bed-knife 10 is provided on its outer face, below its cutting edge, with a plurality of longitudinally spaced vertically disposed and outwardly projecting rib-like projections 46, between which the free extremities of the pelt support fingers 27'-28' may extend, whereby the tops of said projections 46 cooperate with inwardly projected fingers to support the pelt skin right up to the very cutting edge of the bed-knife 10.

Cooperative with said pelt supporting fingers 27'-28', is a novel means for impelling the pelt toward the bed-knife 10, the same being especially effective for feeding the trailing or rear end extremity of the pelt after it has escaped from the nip of the feed rolls 15-17. This means comprises the following mechanism:

Mounted on the upper forward portions of said end frame plates 5 are bearing brackets 47. Journaled to extend between said bearing brackets, above and forwardly off-set relative to the feed rolls 15-17 is a rock shaft 48. Fixed on said rock shaft 48, in suitably spaced apart relation, are rocker members having oppositely extending arms 49 and 50. Pivots connected with the downwardly projecting rocker arms 49 are push-bars 51, which extend forwardly between certain of the upper feed rolls 17, with their free ends lying over the supporting fingers 27'-28', and extending beyond the nip of the feed rolls 15-17 toward the bed-knife 10. In like manner, pivots connected with the upwardly projecting rocker arms 50 are similar push bars 52, which also extend forwardly between 123

others of the upper feed rolls 17, with their free ends lying over the supporting fingers 27'-28', and extending beyond the nip of the feed rolls 15-17 toward the bed-knife 10. Said push-bars 51-52 are respectively yieldably urged toward said supporting fingers 27'-28' by compression springs 53 which are suitably backed by an anchor-plate 54 supported from said bearing brackets 47 to extend across and above said push bars. The means for oscillating said rock-shaft 48 and the rocker arms 49-50 connected therewith, to produce alternated reciprocable movements of said push-bars 51-52, comprises an eccentric crank-element 55 connected with and rotated by an end of said main shaft 7, the same being connected by a connecting rod or link 56, with a crank-arm 57 fixed on an end of said rock-shaft 48. The lower edges of the free end portions of said push-bars 51-52 are provided with forwardly projected gripping teeth 58, which while tending to easily draw outward over the pelt skin on backward movement of the push-bars, will, on forward movement of the latter, engage the pelt skin with strong friction so as to impel the same forward to the cutting point of the machine, especially after the rear end of the pelt escapes the nip of the feed rolls, while at the same time operating to hold the pelt flatly down on the underlying supporting fingers 27'-28' and bed-knife projections 46, so that even and regular skin chips or slivers are produced without loss of valuable fur due to too coarse a chip, undue indragging of the pelt during the cutting operation, or other undesired displacement, wrinkling or shifting of the pelt during the cutting moment.

In the operation of the machine, the pelt, fur side down, is pushed by the operator endwise over the feed table 30 until its forward end is nipped between the feed rolls 15-17. The feed rolls propel the pelt forwardly toward the bed-knife 10, the fur being combed or laid back by the forward movement of the pelt, whereby the bases of the fur filaments are exposed to the cutting action of the revolving cutting blades 9, which, as they pass shearingly along the bed-knife 10, operate to shear off a sliver or chip of the pelt skin thereby at the same time severing from the skin sliver or chip the fur filaments close to the roots of the latter. The severed fur will discharge downwardly into and through the discharge passage 13 to a suitable place of collection. Owing to the reciprocated pelt supporting fingers 27'-28', which, together with the projections 46 of the bed-knife 10, underlie the pelt between the nip of the feed rolls and the cutting edge of said bed-knife, the pelt is supported against sagging or improper disposition right up to the cutting edge of said bed-knife. The reciprocation of said supporting fingers 27'-28', however, operates to alternately retract their forward

extremities, relative to the bed-knife and its projections 46, sufficiently to assure unobstructed access of severed fur to the underlying discharge passage 13, the agitation occurring by reason of the movement of the supporting fingers tending to shake or loosen up the severed fur so that the same will freely fall away into said discharge passage. The alternately reciprocated sets of push-bars 51-52 which are yieldingly pressed against the skin side of the pelt, not only serve to retain the latter smoothly spread as it moves over the supporting fingers to the cutting point of the machine, but also operate as a highly efficient impelling means to assure the smooth and controlled onward movement of the trailing end of the pelt to the cutting point of the machine, after the same escapes the nip of the feed rolls 15-17, thereby assuring uniform cutting consumption of the entire pelt to the end that maximum output of severed fur may be attained without loss, or without production of wasteful scrap ends of pelt with which valuable unsevered fur filaments are carried away.

I am aware that changes may be made in the above described mechanisms as well as in the details of the construction thereof, without departing from the scope of this invention as defined in the appended claims; it is therefore intended that all matter contained in the above description or shown in the accompanying drawings shall be interpreted as illustrative and not in a limiting sense.

I claim:

1. In a fur cutting machine, a cutting mechanism, feed rolls in front of said cutting mechanism by and between which a pelt is fed toward said cutting mechanism, unyielding means underlying the pelt in supporting relation thereto and extending beyond to the nip of said feed rolls to the cutting point of said cutting mechanism, and two sets of reciprocable push-bars, the members of which are alternated with one another, said push-bars having their free ends operative between said feed rolls and said cutting mechanism to retain a pelt smoothly spread on said supporting means, and means to alternately advance and retract said sets of push-bars with impelling effect upon pelt portions lying between said feed rolls and said cutting mechanism.

2. In a fur cutting machine, a cutting mechanism, feed rolls in front of said cutting mechanism by and between which a pelt is fed toward said cutting mechanism, unyielding means underlying the pelt in supporting relation thereto and extending beyond to the nip of said feed rolls to the cutting point of said cutting mechanism, and two sets of reciprocable push-bars, the members of which are alternated with one another, said push-bars having serrated free end portions op-

- erative between said feed rolls and said cutting mechanism to retain a pelt smoothly spread on said supporting means, means to alternately advance and retract said sets of 5 push-bars with impelling effect upon pelt portions lying between said feed rolls and said cutting mechanism, and spring means for yieldingly holding said push-bars in operative engagement with a pelt.
10. 3. In a fur cutting machine having a cutting mechanism, unyielding means to underlie a pelt in supporting relation thereto as it moves to said cutting mechanism, a plurality of sets of reciprocable push-bars, the members of which are alternated with one another, means to yieldably engage said push-bars with a pelt as supported by said supporting means, and means to alternately reciprocate said sets of push-bars to impel a pelt over said 20 supporting means to the cutting mechanism of the machine.
4. In a fur cutting machine, a cutting mechanism, feed rolls by and between which a pelt is fed toward said cutting mechanism, unyielding reciprocable supporter bars having pelt supporting fingers extending beyond the nip of said feed rolls to the cutting mechanism, means to longitudinally reciprocate said bars and fingers in groups whereby withdrawn fingers give additional clearance for the discharge of severed fur from the cutting mechanism, longitudinally reciprocable push-bars having pelt engaging portions operative 25 between said feed rolls and said cutting mechanism, said push-bars being disposed over said supporter bars and fingers, and means to longitudinally reciprocate said push-bars in groups toward and from the cutting mechanism with pelt advancing effect.
30. 5. In a fur cutting machine, a cutting mechanism, feed rolls by and between which a pelt is fed toward said cutting mechanism, unyielding reciprocable supporter bars having pelt supporting fingers extending beyond the nip of said feed rolls to the cutting mechanism, means to longitudinally reciprocate said bars and fingers in groups whereby withdrawn fingers give additional clearance for the discharge of severed fur from the cutting mechanism, longitudinally reciprocable push-bars having serrated pelt engaging portions operative 35 between said feed rolls and said cutting mechanism, said push-bars being disposed over said supporter bars and fingers, and means to longitudinally reciprocate said push-bars in groups toward and from the cutting mechanism with pelt advancing effect, and means to yieldingly urge said push-bars into operative engagement with a supported pelt.
40. 6. In a fur cutting machine, a cutting mechanism, feed rolls by and between which a pelt is fed toward said cutting mechanism, reciprocable bars having pelt supporting fingers extending beyond the nip of said feed rolls
- to the cutting mechanism, means to longitudinally reciprocate said bars and fingers in groups whereby withdrawn fingers give additional clearance for the discharge of severed fur from the cutting mechanism, push-bars having pelt engaging portions operative between said feed rolls and said cutting mechanism, said push-bars being disposed over said bars and fingers, and means to longitudinally reciprocate said push-bars in groups toward and from the cutting mechanism with pelt advancing effect, said push-bars having serrated pelt gripping portions, and means to yieldingly urge said gripping portions into operative engagement with a supported pelt.
- In testimony that I claim the invention set forth above I have hereunto set my hand this 9th day of June, 1931.
- ROBERT H. PLASS.
